CLAIM

The ornamental design for a finger-mountable holder for a writing instrument, as shown and described.

DESCRIPTION

FIG. 1 is a top, right front perspective view of a finger-mountable holder for a writing instrument showing my new design;

FIG. 2 is a top plan view thereof;

FIG. 3 is a front elevational view thereof;

FIG. 4 is a right side elevational view, the left side being a mirror image thereof;

FIG. 5 is a rear elevational view thereof;

FIG. 6 is a bottom plan view thereof;

FIG. 7 is a cross-sectional view taken in the direction of arrows 7—7 in FIG. 5; and,

FIG. 8 is a rear perspective view thereof, the finger fragment and writing instrument fragment being depicted by means of broken lines for illustrative purposes only and forming no part of the claimed design.
